US0D1018496S

(12) **United States Design Patent** (10) **Patent No.:** **US D1,018,496 S**
(45) **Date of Patent:** **** Mar. 19, 2024**

(54) **HEADPHONE**

(71) Applicant: **Audio-Technica Corporation**, Tokyo (JP)

(72) Inventors: **Mika Yoshino**, Tokyo (JP); **Yuki Nojiri**, Kanagawa (JP)

(73) Assignee: **Audio-Technica Corporation**, Tokyo (JP)

(**) Term: **15 Years**

(21) Appl. No.: **29/825,125**

(22) Filed: **Jan. 28, 2022**

(30) **Foreign Application Priority Data**

Aug. 4, 2021 (JP) 2021-016966

(51) **LOC (14) Cl.** **14-01**

(52) **U.S. Cl.**

USPC **D14/205**

(57) **CLAIM**

The ornamental design for a headphone, as shown and described.

DESCRIPTION

FIG. 1 is a front perspective view of a headphone, showing the new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

Portions of the drawings shown in broken lines are parts of the headphone which form no part of the claimed design.

1 Claim, 6 Drawing Sheets
